CLAIM

The ornamental design for a pet travel bed, as shown and described.

DESCRIPTION

FIG. 1 is an outside front perspective view of a portable pet bed in the closed position showing my new design, the opposite or rear side being substantially identical in appearance;

FIG. 2 is an inside top perspective view thereof;

FIG. 3 is an outside plan view thereof;

FIG. 4 is a side elevational view thereof the opposite side being a mirror image of the side shown; and,

FIG. 5 is an inside plan view thereof.

FIG. 5
